UNITED STATES PATENT OFFICE.

EDWARD P. BECKWITH, OF GARRISON, NEW YORK.

ELECTRIC INCANDESCENT LAMP.

1,122,568.

Specification of Letters Patent. Patented Dec. 29, 1914.

Application filed January 22, 1912. Serial No. 672,685.

To all whom it may concern:

Be it known that I, EDWARD P. BECKWITH, a citizen of the United States, residing at Garrison, county of Putnam, and State of New York, have invented certain new and useful Improvements in Electric Incandescent Lamps, fully described and represented in the following specification and the accompanying drawings, forming a part of the same.

This invention relates to improvements in electric incandescent lamps.

In certain classes of incandescent lamps it is desirable to employ a filament which is relatively long with respect to the capacity of the bulb of the lamp and to accomplish this the filament is given a number of turns or convolutions within the bulb. The fragile character of the filament when it is thus convoluted requires that it be supported at one or more points in order to prevent breakage due to the jars or vibrations to which the lamp is subjected. It is customary, therefore, in such lamps to provide a holder for the filament which is supported within the bulb, the filament being in contact with the holder at a number of points, the number of contact points depending upon the length of the filament to be used and the size of the bulb.

The tungsten filament lamps now generally used comprise a central glass standard or rod into which is fused a number of supporting wires of electric conducting material, such as copper, tungsten or molybdenum, or some substance capable of withstanding the high temperature of the filament. The ends of these wires are made hook shape, and the filament is strung or supported on the hooks. In this construction, the central glass standard not only serves to carry the supporting wires, but also to insulate them from each other, so that short circuiting is prevented. The supporting wires used in such constructions are good heat conductors and there is considerable cooling of the filament at its points of contact therewith. This is especially true when the supporting wires are of copper which is the material generally employed. This cooling of the filament results in a measurable loss of light and a consequent reduction in the candle power and efficiency of the lamp. Further, the supporting wires become sufficiently heated to cause the occluded gases in the wires to be given off,

thus impairing the vacuum of the lamp. Again, the central glass support is rigid or stiff, and an external shock, even when it does not break the support is liable to break the filament. Further, since the central glass rod must be of considerable size and is located between the lighted body and the part of the filament on the side opposite the body, the rod materially reduces the candle power of the lamp.

In another construction of lamp a support was provided comprising a central glass standard carrying supporting hooks made of thoria. These hooks were usually prepared by forming a wet compound of pulverized thoria and a carbonaceous material, molding the compound into threadlike strips, bending the strips to shape, and then burning out the carbonaceous material. These thoria hooks were then tied to the glass standard by short wires which were fused into the standard at one end and into the thoria holders at the other end.

Another construction of holder involved the employment of a small molded block of refractory combinations of tantalum, niobium and vanadium, or similar comparatively infusible metals, the block being carried by an anchored wire.

The constructions last referred to had the advantage of acting as heat insulators, but it was found in practice that they gave off considerable gas, thereby impairing the vacuum of the lamp. In order to avoid this, these molded holders had to be prepared by special processes of manufacture, and as the materials of these holders were very expensive and the processes of manufacture were also expensive, the cost of such holders was exceedingly high. Further, such molded holders were fragile. For these reasons, the commercial use of the holders referred to has been discontinued, and the holders now employed almost universally are of the type first described embodying the glass standard and the metal supporting hooks.

The present invention has for its object to produce an incandescent lamp having a holder for the filament which not only presents high heat and electric insulating qualities but which is also cheap in construction, does not give off gas during the operation of the lamp and is flexible, thus enabling the lamp to withstand shocks, so that breakage is reduced.

A further object of the invention is to produce an improved incandescent lamp in which a comparatively slender and flexible standard, such, for instance, as wire, is employed and a filament holder, the filament being insulated from the holder at the point or points of contact therewith.

With these and other objects not specifically referred to in view the invention consists in certain constructions and in certain parts, improvements and combinations as will be hereinafter fully described and then specifically pointed out.

In the accompanying drawings, the figure illustrates, in section, and partly in section, an electric incandescent lamp constructed in accordance with the invention.

Referring to said drawing, 1 indicates the usual glass bulb, 2 the threaded cap, and 3 the usual insulating section through which the leading-in wires, indicated at 4, pass. These parts are or may be of usual construction. Lamps constructed in accordance with the invention will employ a holder for 25 positioning the filament in the lamp. While the construction of the holder may be varied within wide limits, the holder may well comprise a comparatively slender central standard from which extends a number of 30 metallic supports. Excellent results are attained by using a central standard made of steel wire, 5, say, about twenty mills in diameter, as such a wire does not interfere to any considerable degree with the horizontal 35 candle power of the lamp, and has the further advantage that it is flexible and can yield to external shock, thus lessening the liability of breakage of the filament. This standard may be supported in the insulating 40 section for the leading-in wires, by being fused therein, as indicated in the drawing. When the invention is embodied in a lamp comprising a central holder there may be employed in connection therewith a number 45 of supports 6 upon which the filament is strung. These supports may, as indicated in the drawing, consist of very light wire 7 which may be conveniently connected to the central standard by being wound upon it.

50 In lamps embodying the invention, the holder, whatever be its construction in other respects, will be coated at the points of contact with the filament therewith, with an insulating material which has high heat and electric insulating qualities and which does not give off gas under the conditions in which the lamp is used. Compositions which include glass as an ingredient have been successfully used, a composition consisting of bauxite 2 parts, clay 1.5 parts, and glass 2 parts by weight having been found to be excellent for this purpose. The insulating material employed may be variously applied. In using the composition referred to, it may be satisfactorily applied

by making it into a thin paste with water and dipping the supports into the paste, the supports being then heated to drive off the moisture and fire the composition firmly thereto.

A lamp structure as described has the advantages that it may be cheaply made. Further, the coating employed prevents the cooling of the filament at the point or points of contact with the support, thus avoiding 75 consequent loss of light, and the vacuum of the lamp is not impaired by gases given off from the supporting wires. Further, the configuration of the holder may be widely varied, and the filament may be supported 80 at as many points within the lamp as may be found to be desirable. This is of great importance, as it enables a great variety of lamps to be constructed differing in light distribution or concentration. Further, since 85 a central glass support is not required for insulating purposes a slender and comparatively flexible support may be used, thus decreasing the liability of breakage of the filament. Such a slender support has the 90 further advantage that it does not cut off the horizontal candle power of the lamp which is, therefore, slightly higher than in lamps in which a comparatively large central glass support is employed.

As has been indicated, changes and variations may be made in the construction by which the invention is carried into effect. The invention is not, therefore, to be confined to the particular construction hereinbefore described and illustrated in the accompanying drawing.

What is claimed is:—

1. In an electric incandescent lamp, the combination with the filament, of a holder 105 for determining the position of the filament, the holder being coated at the point of contact with the filament with a refractory material having high electric and heat insulating qualities.

2. In an electric incandescent lamp, the combination with the filament, of a flexible metallic holder for determining the position of the filament, the holder being coated with refractory insulating material at the point or points of contact therewith.

3. In an electric incandescent lamp, the combination with the filament, of a metallic holder comprising a wire standard, and means for supporting the filament at a number of points, the supporting means being coated at the points of contact with the filament with a refractory material having high electric and heat insulating qualities.

4. In an electric incandescent lamp, the combination with the filament, of a metallic holder comprising a central wire standard, and means for supporting the filament at a number of points, the supporting means being coated at the points of contact with the

- filament with a refractory material having high electric and heat insulating qualities.
5. In an electric incandescent lamp, the combination with the filament, of a flexible metallic holder for determining the position of the filament, the holder being coated at the point or points of contact with the filament with a composition of refractory material, the composition being fired on the holder.
10. In an electric incandescent lamp, the combination with the filament, of a metallic holder comprising a wire standard, and means for supporting the filament at a number of points, the supporting means being coated at the points of contact with the filament with a refractory composition fired thereon, said composition having high heat and electric insulating qualities.
15. In an electric incandescent lamp, the combination with the filament, of a flexible metallic holder for determining the position of the filament, the holder being coated with a composition of refractory material of which glass is an element at the point or points of contact with the filament, the composition being fired on the holder.
20. In an electric incandescent lamp, the combination with the filament, of a metallic

holder comprising a wire standard and 30 means for supporting the filament at a number of points, the supporting means being coated at the points of contact with the filament with a refractory composition of which glass is an element fired thereon, said 35 composition having high heat and electric insulating qualities.

9. In an electric incandescent lamp, the combination with the filament, of a holder for determining the position of the filament, the holder being coated with a composition consisting of bauxite, clay and glass in substantially the proportions described fired thereon.

10. In an electric incandescent lamp, the combination with the filament, of a holder comprising a wire standard and a plurality of wire supports, the supports being coated with a refractory material consisting principally of bauxite, clay and glass.

In testimony whereof, I have hereunto set my hand, in the presence of two subscribing witnesses.

EDWARD P. BECKWITH.
